(57) **ABSTRACT**

A device is provided for aligning magnetic or magnetizable particles, which are contained in a coating that is applied to a first side of a web-type or a sheet-type substrate. An application device is arranged in the transport path of the substrate, by the use of which, the coating is applied or is applicable to the first side of the substrate, in at least one application site. A first cylinder, which is embodied as a magnetic cylinder, is arranged in the transport path of the substrate to be transported downstream of the application device and comprises a plurality of elements creating a magnetic field in the region of the outer periphery of the first cylinder. Another cylinder, which is embodied as a magnetic cylinder, is arranged in the transport path of the substrate to

(Continued)

be transported and comprises a plurality of elements creating a magnetic field in the region of the outer periphery of that cylinder. A drying device or an hardening device is arranged on the transport path between a site of a winding-on of the substrate on the first cylinder and a site of a winding-on of the other cylinder. The first cylinder, which is embodied as the magnetic cylinder, is arranged in the transport path of the substrate to be transported on the second side thereof. The drying or the hardening device is oriented in the transport path of the substrate to be transported on the first side thereof.

**DEVICE FOR APPLYING AND ALIGNING
MAGNETIC OR MAGNETIZABLE
PARTICLES ON A WEB-TYPE OR
SHEET-TYPE SUBSTRATE**

**CROSS-REFERENCE TO RELATED
APPLICATIONS**

This application is the U.S. National Phase, under 35 U.S.C. § 371, of PCT/EP2019/050889, filed Jan. 15, 2019; published as WO 2019/201481 A1 on Oct. 24, 2019, and claiming priority to DE 10 2018 205 883.0, filed Apr. 18, 2018, the disclosures of which are expressly incorporated herein in their entireties by reference.

FIELD OF THE INVENTION

The present invention relates to devices, a machine having such a device, and a method for applying and aligning magnetic or magnetizable particles on a web-format or sheet-format substrate. A device is usable for aligning magnetic or magnetizable particles contained in a coating medium that is applied to a first side of a web-format or a sheet-format. The device includes an application system arranged in the transport path of the substrate, by the use of which application system the coating medium is or can be applied at at least one application point to the first side of the substrate. A first cylinder, which is embodied as a magnetic cylinder, is arranged downstream of the application system in the transport path of the substrate to be conveyed and which has, in the region of its outer circumference, a plurality of elements that induce a magnetic field. An additional cylinder, which is embodied as a magnetic cylinder, is arranged in the transport path of the substrate to be conveyed and has, in the region of its outer circumference, a plurality of elements that induce a magnetic field. One of a drying and a curing unit is arranged on the transport path between the point at which a substrate runs onto the first cylinder and the point at which it runs onto the additional cylinder. The first cylinder, which is embodied as a magnetic cylinder, is arranged at a first cylinder position in the transport path of the substrate to be conveyed. The second cylinder, that follows the first cylinder in the transport path, is arranged at a second cylinder position. The second cylinder is arranged on the opposite side of the transport path from the first cylinder. The first cylinder, provided at the first cylinder position, the second cylinder, and a third cylinder that follows the second cylinder in the transport path at a third cylinder position, are or can be mounted rotatably in frame walls of a frame. A machine, in particular a security printing press, for producing optically variable image elements on a substrate, comprises a substrate infeed, in particular embodied as a sheet feeder and at least one printing unit have at least one printing couple, in particular a screen printing couple, by the use of which, a substrate that is guided along a transport path through the machine is or can be printed at least on a first side. A product receiving unit, which is embodied in particular as a pile delivery, and a device for aligning magnetic or magnetizable particles, are provided in a transport path of the substrate between the printing unit and the product receiving unit. A method is provided for applying and aligning magnetic or magnetizable particles contained in a coating medium. The coating medium containing the magnetic or magnetizable particles is applied, in an application system, to a first side of a web-format or a sheet-format substrate. Downstream of the application system, first the substrate is guided with its first

side, which contains the coating medium, facing outward, over a first cylinder that has magnetic elements in the region of its outer circumference, in order to align at least a portion of the particles. After the substrate has run onto the first cylinder, it passes a drying or a curing unit that is directed towards the first side of the substrate.

BACKGROUND OF THE INVENTION

10 A printing press known from EP 2 845 732 B1 comprises a screen printing unit and a device for aligning magnetic or magnetizable particles that are contained in the printing ink or the varnish; said device comprises a cylinder having on its circumference a plurality of elements that induce a magnetic field, along with a dryer directed toward a point along the transport path at which the substrate has not yet left the cylinder.

15 In EP 3 178 569 A1, substrate is coated on one side with a coating medium containing magnetic or magnetizable particles and, on the transport path downstream of the coating point, said substrate is first guided on that side over a first cylinder comprising at least one element that generates a magnetic field, and is then guided with its second side over another cylinder comprising at least one element that generates a magnetic field. As the substrate is being guided over the first cylinder, the coating is dried through a mask and through the substrate from the second side thereof.

20 CN 105034570 B discloses a device for producing a substrate that is printed with magnetic coating medium, in which the substrate is coated on a first side by a printing device, and then is guided on said first side over a first and then a second cylinder in succession, each having elements that generate a magnetic field, after which said substrate is dried on the twice-printed side by means of a curing device, for example.

25 In the WO 2016/015973 A1, coating medium containing magnetic or magnetizable particles is applied in one exemplary embodiment to a substrate surface; the particles are then aligned by means of a magnet provided on the second side while at the same time being dried over only a portion of the surface from the first side using a mask, after which the undried portion is aligned from the first side by means of a magnet while at the same time being dried from the second side by means of a dryer.

30 35 40 45 EP 2 114 678 B1 discloses a cylinder which, in the region of its outer circumference, comprises a plurality of elements that induce a magnetic field in or on a plurality of ring elements that are spaced apart axially and can be positioned in an axial direction on a shaft; in or on each of said ring elements, a plurality of magnetic elements are in turn arranged one after another in the circumferential direction.

US 2006/0219107 A1 discloses a printing machine having a device for aligning magnetic flakes in the form of an impression cylinder that is furnished with magnets, which 50 55 60 65 cooperates with a first and a second screen cylinder to form two print positions. In a first variant, in place of the impression cylinder, an unloading cylinder equipped with magnets is provided as the magnetic cylinder, which receives the printing substrate from the impression cylinder. In a second variant, in place of the impression cylinder, an intermediate cylinder equipped with magnets and provided downstream of the unloading cylinder in the printing substrate path is provided as the magnetic cylinder. In a further variant, magnets can be provided on the impression cylinder and/or on the unloading cylinder and/or on the intermediate cylinder. However, the two variants would offer the advantage that the impression cylinder is not modified and as a

result, there is no risk of lumps or indentations in the printing substrate due to an uneven surface on the impression cylinder. If the two screen cylinders are to be used for printing at the same points one on top of the other, a system for drying the ink applied by the first screen cylinder, for example a UV lamp or an equivalent system, must be added.

WO 2016/067247 A1 discloses a printing press comprising a device for magnetic orientation, which has a magnetic cylinder over which the printing substrate, which has been furnished upstream with the fluid containing magnetic particles, is guided. A dryer, which is preferably embodied as a UV LED dryer, is directed toward the circumference of the magnetic cylinder.

DE 11 2012 006 348 T5 discloses a printing press having a screen printing couple and downstream thereof, a magnetic alignment cylinder. The latter is followed by a transport cylinder along with a transport and drying cylinder. The magnetic cylinder and the transport and drying cylinder comprise, in their interior, two air chambers, which are located between a respective spindle and a respective cylinder body and which are separated from one another by two air chamber partitioning bars running between the spindle and the cylinder body. The relationships between spindle, cylinder body, and air chamber partitioning bars are the same for both cylinders.

WO 2016/030819 A1 discloses a combination printing press that comprises a screen printing unit and, downstream thereof, an intaglio printing unit. Said screen printing unit comprises a magnetic cylinder downstream of the print position, followed by a sheet transfer cylinder and a drying cylinder.

US 2017/0190197 A1 discloses a combination printing press that comprises a screen printing unit and, downstream thereof, a numbering printing unit. Said screen printing unit comprises a magnetic cylinder downstream of the print position, followed by a sheet transfer cylinder and an impression cylinder of the numbering printing unit.

SUMMARY OF THE INVENTION

The object of the present invention is to create devices, a machine having such a device, and a method for applying and aligning magnetic or magnetizable particles on a web-format or sheet-format substrate.

The object is achieved according to the invention by the provision of the first cylinder embodied as the magnetic cylinder arranged in the transport path of the substrate to be conveyed, on the second side thereof. The drying or curing unit is directed in the transport path of the substrate to be conveyed toward the first side thereof. Bearing assemblies, for receiving the journals of the cylinder to be arranged at ones of the second and the third site are configured such that the ones of the second and the third cylinder positions can be equipped or configured either with a cylinder configured as a magnetic cylinder having a plurality of elements that induce a magnetic field, corresponding to the first cylinder, or with the cylinder configured as a transport cylinder. After the substrate has left the first cylinder, it is guided downstream of the first drying or curing unit, over an additional cylinder that has magnetic elements in the region of its outer circumference, in order to align at least a portion of the particles.

The advantages that are achievable by the invention consist in particular in that substrates having a particularly wide range of optically variable image elements and/or image elements of particularly high quality can be produced.

In an embodiment or configuration according to the invention comprising two magnetic cylinders and preferably intermediate drying, complex optically variable image elements can be produced, if desired with particularly sharp borders.

An advantageous embodiment, e.g. of modular configuration, in which one or more cylinder positions can optionally be populated by a transport cylinder and a magnetic cylinder provides a substantial increase for the operator in the spectrum of possible effects that can be produced.

A device according to the invention for aligning magnetic or magnetizable particles contained in a coating medium that is applied to a first side of a web-format or sheet-format substrate, said device comprising an application system, in particular a printing unit comprising a printing couple cylinder, which is arranged in the transport path of the printing substrate and by means of which the coating medium is and/or can be applied at at least one application point to the first side of the substrate, a first cylinder embodied as a magnetic cylinder, which is arranged downstream of the application system in the transport path of the substrate to be conveyed, in particular downstream of all the printing couple cylinders participating at one or more print positions of the printing unit, and which, in the region of its outer circumference, has a plurality of elements that induce a magnetic field, hereinafter also referred to as magnetic elements, an additional cylinder embodied as a magnetic cylinder, which is arranged in the transport path of the substrate to be conveyed and which, in the region of its outer circumference, has a plurality of elements that induce a magnetic field, and a drying and/or curing unit, which is arranged on the transport path between the point at which the substrate runs onto the first cylinder and the point at which said substrate runs onto the additional cylinder.

In a particularly preferred embodiment of the device, the first cylinder, embodied as a magnetic cylinder, is arranged in the transport path of the substrate to be conveyed on the second side thereof, and the drying and/or curing unit is directed toward the first side of said substrate in the transport path of the printing substrate to be conveyed.

In an advantageous embodiment of the device, the additional cylinder is provided as a third cylinder downstream of a second cylinder, which is situated downstream of the first cylinder, said third cylinder being arranged in the transport path of the substrate to be conveyed on the same side of the transport path as the first cylinder.

In an advantageous configuration, the second cylinder is embodied as a transport cylinder, via which the substrate is and/or can be fed from the first cylinder to the third cylinder.

In addition to or in place of the above device, a particularly advantageous solution is made possible by a device for aligning magnetic or magnetizable particles contained in a coating medium that is applied to a first side of a web-format or sheet-format substrate, which device comprises a first cylinder embodied as a magnetic cylinder, which is arranged at a first cylinder position in the transport path of the substrate to be conveyed and which has, in the region of its outer circumference, a plurality of elements that induce a magnetic field, and a second cylinder, which follows the first cylinder at a second cylinder position in the transport path and which is arranged on the other side of the transport path from the first cylinder.

In a particularly preferred embodiment of the device, the first cylinder provided at the first cylinder position, the second cylinder, and a third cylinder that follows the second cylinder at a third cylinder position in the transport path are or can be rotatably mounted in frame walls of a frame, the

second cylinder being embodied, in particular, solely as a transport cylinder, i.e. without magnetic elements on its circumference.

In a particularly advantageous refinement, the bearing means for receiving the journals of the cylinder to be arranged at the second and/or the third site are configured such that the second and/or the third cylinder position can be equipped and/or configured either with a magnetic cylinder having a plurality of elements that induce a magnetic field, corresponding to the first cylinder, or with a transport cylinder, and/or the bearing means for receiving the journals of the cylinder to be arranged at the first site are configured such that the first cylinder position can optionally be equipped and/or configured with a transport cylinder that corresponds to the second cylinder, rather than with the magnetic cylinder.

In a particularly advantageous embodiment of the device, the third cylinder position is equipped and/or configured with a cylinder embodied as a magnetic cylinder, which has, in the region of its outer circumference, a plurality of elements that induce a magnetic field. In an alternative configuration, the third cylinder position can be equipped and/or configured with a cylinder embodied as a transport cylinder.

The bearing means embodied for receiving either a magnetic cylinder or a transport cylinder are preferably configured as having radial bearings for receiving journals of the same diameter for the cylinders configured as either magnetic or transport cylinders, and/or on the frame at the relevant cylinder positions are configured as having receiving means for receiving radial bearings of the same outer diameter for the magnetic and transport cylinders.

The first cylinder is preferably arranged in the transport path of the substrate to be conveyed, in each case on the second side of said substrate.

In an embodiment of a cylinder that is particularly preferred on its own or in conjunction with a device as described above, in particular a cylinder for aligning magnetic or magnetizable particles contained in a coating medium that is applied to a first side of a web-format or sheet-format substrate, and which cylinder has, in the region of its outer circumference, a plurality of elements that induce a magnetic field, i.e. magnetic elements, the magnetic elements are arranged in or on a plurality of ring elements that are spaced apart from one another axially and are positionable in an axial direction on a shaft, in or on each of which ring elements a plurality of magnetic elements are in turn arranged one after another in the circumferential direction.

In an advantageous embodiment of an aforementioned device, the cylinders comprise holding means for transporting the substrate in the form of printing substrate sheets, wherein the substrate in the form of printing substrate sheets is transferred directly between the mutually adjacent cylinders.

In an advantageous embodiment, a chain gripper system having gripper bars supported by continuous revolving chains is provided in the transport path between the application system and the first cylinder.

A first drying and/or curing unit provided, e.g., in an aforementioned device is preferably configured to act on the substrate to be treated in sections that are spaced apart from one another transversely to the direction of transport and/or said unit is directed toward a point on the transport path lying on the circumference of the first cylinder. Said sections are preferably adjustable in terms of their position transversely to the direction of transport and/or from which the drying and/or curing unit comprises a plurality of radiation

sources, preferably UV radiation sources such as UV LED's in particular, which are provided in a plurality of dryer heads that define the sections or in an array of radiation sources that is continuous over the maximum substrate width to be treated but that can be activated in sections.

A second drying and/or curing unit provided, e.g., in an aforementioned device preferably comprises a plurality of radiation sources, preferably UV radiation sources such as UV LED's in particular, which are provided in an array of radiation sources that is continuous over the maximum substrate width to be treated.

In a particularly preferable embodiment of the cylinder, at least two adjacent ring elements, preferably all ring elements, each have a cover element that forms a part of the cylindrical shell surface of the cylinder and that extends in the circumferential direction at least over the circumferential region that is equipped with the magnetic elements, wherein the cover elements of two mutually adjacent ring elements each have, on the axially facing sides thereof, a plurality of protrusions alternating in the circumferential direction with recesses and offset in the circumferential direction such that, with a relative movement of the two ring elements toward one another, the protrusions on the cover element of the one ring element engage respectively in a tooth-like manner in corresponding recesses of the other ring element and can overlap one another as viewed in the circumferential direction.

A preferable machine, in particular a security printing press, for producing optically variable image elements on a substrate, comprises a printing substrate infeed, in particular embodied as a sheet feeder. At least one printing unit has at least one printing couple, in particular a screen printing couple, by means of which, a substrate that is guided along a transport path through the machine is and/or can be printed at least on a first side. A product receiving unit, embodied in particular as a pile delivery, and a device for aligning magnetic or magnetizable particles, as described by one of the aforementioned embodiments or variants and/or an embodiment or variant described in the specifications are provided in the transport path of the substrate between printing unit and product receiving unit.

The following are preferably performed, in particular inline, i.e. without interruption in transport between the steps to be carried out: a coating medium containing the particles is preferably applied to the substrate, the substrate is guided over a first cylinder that has magnetic elements in the region of its outer circumference, the coating medium is dried, preferably partially, while the substrate is still in contact with the first cylinder or thereafter, the substrate is guided over an additional cylinder that has magnetic elements in the region of its outer circumference, and the coating medium is dried, over its entire surface or partially, while the substrate is still in contact with the additional cylinder or thereafter.

Further details and variants may be found in the following exemplary embodiments and may be combined respectively with any of the embodiments set out above for the device, the cylinder, and/or the machine, provided said combination is not contradicted.

BRIEF DESCRIPTION OF THE DRAWINGS

Exemplary embodiments of the invention are illustrated in the set of drawings and will be described in greater detail below.

In the drawings:

FIG. 1a shows a first exemplary embodiment of a machine for producing optically variable image elements on a substrate;

FIG. 1b shows a second exemplary embodiment of that machine;

FIG. 2a is a schematic top plan depiction of a substrate printed with optically variable coating medium in print elements;

FIG. 2b is a schematic side elevation depiction of the substrate of FIG. 2a;

FIG. 3a is a schematic top plan depiction of a substrate furnished with optically variable image elements;

FIG. 3b is a schematic side elevation depiction of the substrate of FIG. 3a;

FIG. 4 shows an enlarged view of the printing unit from FIG. 1;

FIG. 5 shows an enlarged view of the device for aligning magnetic or magnetizable particles from FIG. 1;

FIG. 6 shows a side view into the open side of a device for aligning magnetic or magnetizable particles;

FIG. 7 shows a vertical section, transversely to the direction of transport, of the device according to FIG. 6;

FIG. 8 shows an oblique view of the device for aligning magnetic or magnetizable particles with a first variant of the first drying and/or curing unit;

FIG. 9 shows an oblique view of the device for aligning magnetic or magnetizable particles with a second variant of the first drying and/or curing unit;

FIG. 10 shows an oblique view of an embodiment of a magnetic cylinder;

FIG. 11 shows an oblique view of an embodiment of a transport cylinder;

FIG. 12a is a schematic depiction of a first embodiment or configuration of a magnetic cylinder;

FIG. 12b is a schematic depiction of a second embodiment or configuration thereof;

FIG. 12c is a schematic depiction of a third embodiment or configuration thereof;

FIG. 12d is a schematic depiction of a fourth embodiment or configuration thereof;

FIG. 12e is a schematic depiction of a fifth embodiment or configuration thereof; and

FIG. 13 is a schematic depiction of an advantageous embodiment of a magnetic cylinder.

DESCRIPTION OF PREFERRED EMBODIMENTS

A machine 01, e.g. a printing press 01, in particular a security printing press 01, for producing optically variable image elements 03 on a substrate 02, e.g. a web-format or sheet-format printing substrate 02, comprises an application system 04, e.g. a printing unit 04, by means of which optically variable coating medium 06, e.g. optically variable printing ink 06 or varnish 06, can be applied to least one application point, e.g. printing point, on at least a first side of the substrate 02, e.g. the printing substrate 02, over the entire surface or in sub-regions thereof, in the form of print elements 08, and comprises a device 07 for aligning the optically variable effect in the image elements 03 by orienting the particles responsible for the optical variability, which are contained in the optically variable coating medium 06 that is applied to the substrate 02 (see, e.g., FIG. 1). In the following, said device 07 is also referred to simply as the alignment device 07. Said alignment device 07 is provided in particular in the transport path downstream of the appli-

cation system. Thus, it is provided downstream of the application system embodied as a printing unit particularly in the sense that it does not comprise any printing couple cylinder that forms the print position and/or it lies in the transport path downstream of all the printing couple cylinders of the printing unit 04 that are involved in one or more print positions.

The print elements 08 composed of variable coating medium 06, which are applied to the substrate 02 by the application system 04 prior to treatment by the alignment device 07, may correspond in size and position to the optically variable image elements 03 to be produced (see, e.g., FIGS. 2 and 3) or may optionally be larger than this, if applicable even extending over the surface of multiple copies 09. In the case of larger print elements 08, an optically variable image element 03 is not produced, for example, by means of alignment over the entire surface coated with the optically variable coating medium 06.

The particles responsible for optical variability here are magnetic or magnetizable, non-spherical particles, e.g. pigment particles, hereinafter also referred to simply as magnetic flakes, contained in the coating medium 06, e.g. the printing ink 06 or the varnish 06.

The machine 01 is preferably configured for producing copies 09, e.g. securities 09, in particular banknotes 09, or for producing intermediate products used for such securities 09, e.g. print images of multiple printing substrate sections containing such securities 09. The substrate 02, e.g. printing substrate 02, may be in the form of paper, e.g. cellulose-based or preferably cotton fiber-based paper, a plastic polymer, or a hybrid product of these. Before being coated in the aforementioned application system 04, said printing substrate may be uncoated or may already have been coated, it may be unprinted or may already have been printed one or more times, or otherwise mechanically processed. On a longitudinal section of web-format substrate 02 or on a sheet of a sheet-format substrate 02, multiple copies 09, e.g. banknotes 09 to be produced, preferably are or are to be arranged in a row side by side, and multiple such rows of copies 09 or the printed image thereof preferably are or are to be arranged one after another in the direction of transport T, during the course of processing of the substrate 02 (see, e.g., FIG. 2 and FIG. 3).

The machine 01 embodied as a printing press 01 can generally comprise one or more printing units 04 having one or more printing couples of any printing method. In a preferred embodiment, however, said machine comprises a printing unit 04 having at least one printing couple 11; 12 that operates according to the flexographic printing method or preferably according to the screen printing method, by means of which the optically variable coating medium 06 is or can be applied to a first side of the printing substrate 02. The aforementioned printing methods, in particular the screen printing method, allow a thicker layer to be applied than is possible with other printing methods. The term the “first side” of the substrate 02 or printing substrate 02 has been chosen arbitrarily and is intended to denote the side of the printing substrate 02 to which the optically variable coating medium 06 is or has been or may be applied.

In the depicted and preferred embodiment, the printing press 01 comprises a substrate infeed or printing substrate infeed 13, e.g. a roll unwinder 13 or preferably a sheet feeder 13, by which the web-format or preferably sheet-format printing substrate 02 is or can be fed, optionally via additional printing or processing units, to the printing unit 04, e.g. the flexographic or more particularly the screen printing unit 04, which has at least one printing couple 11; 12, e.g. a

flexographic or more particularly a screen printing couple 11; 12, which applies the optically variable coating medium 06. In the depicted and advantageous embodiment, two screen printing couples 11; 12 are provided, which are preferably combined in the same printing unit 04 and each of which forms, between a forme cylinder 14; 16, e.g. a screen printing cylinder 14; 16, and a shared impression cylinder 17, two printing points for the same side of the printing substrate 02, in this case the first side (see, e.g., FIG. 4). In the transport path between the two printing points, a drying and/or curing unit 18, e.g. a UV dryer 18, can be provided, which is directed toward the first side of a printing substrate 02 to be conveyed through the printing unit 04. One or both of the screen printing couples 11; 12 may apply or be capable of applying optically variable coating medium 06. Impression cylinders and forme cylinders 17; 14; 16 are also referred to as printing couple cylinders 14; 16; 17.

From the printing unit 04 that applies the optically variable coating medium 06, the printing substrate 02 can be fed via conveying means of a first conveyor system 19 to the alignment device 07. In the case of web-format printing substrate 02, said means may be one or more positively driven or non-driven rollers, via which the printing substrate 02 is or can be guided into the alignment device 07 on the input side thereof. In the preferred case of sheet-format printing substrate 02, i.e. individual printing substrate sheets 02 that pass through the machine 01, said conveying means are provided in the form of sheet-conveying means.

In an embodiment not shown here, said sheet-conveying means may be formed by one or more transfer cylinders or transfer drums that receive the printing substrate sheet 02 from the printing unit 04, e.g. from the impression cylinder 17, and deliver it to the alignment device 07 on the input side thereof, optionally via a conveyor system having one or more transfer cylinders or transfer drums. In another advantageous embodiment described here, however, the first conveyor system 19 is embodied as a revolving gripper conveyor 19, e.g. what is known as a chain gripper system 19, which comprises continuous pulling means 21, e.g. continuous chains 21, revolving on both sides of the frame and carrying gripper bars 22 that extend transversely to the direction of transport. The gripper bars 22 can grip the leading ends of the sheets and can thus transport printing substrate sheets 02 along the conveying path and deliver said sheets to the corresponding conveying or receiving means at the intended location. A sprocket 23; 24, also called a chain gripper wheel 23; 24, is preferably located at least in the region where the printing substrate sheet 02 is received from the printing unit 04 and in the region where said sheet is delivered to the alignment device 07.

After passing through the alignment device 07, which will be described in greater detail below, the printing substrate 02 can be guided via conveying means of an additional, e.g. second conveyor system 26 to a product receiving unit 27 for receiving the printing substrate 02 that has been treated and/or processed in the machine 01, e.g. a winder 27 in the case of web-format substrate 02 or a pile delivery 27 in the preferred case of sheet-format substrate 02. In the case of web-format printing substrate 02, said conveying means can again be one or more positively driven or non-driven rollers that carry the transport path of the first conveyor system 19 forward and through the alignment device 07 and via which the printing substrate 02 is or can be guided into the winder 27 on the input side thereof. In the preferred case of sheet-format printing substrate 02, the conveying means are provided in the form of sheet-conveying means. As above, said sheet-conveying means may be in the form of one or

more transfer cylinders or drums, which receive the printing substrate sheet 02 from the alignment device 07 and deliver it to the pile delivery 27 downstream. Preferably, the second conveyor system 26, like the first, is configured as a revolving gripper conveyor 26, e.g. a chain gripper system 26 having revolving continuous pulling means 28, e.g. continuous chains 28, one or more sprockets 31; 32 or chain gripper wheels 31; 32, and gripper bars 29, by means of which the printing substrate sheets 02 are received from the transport path section of the alignment device 07 and are fed, e.g., to the pile delivery 27 (see, e.g., FIG. 1, variant a)). On the transport path leading away from the alignment device 07, an additional drying unit having one or more dryers 34, e.g. radiation dryers 34, directed toward the first side of the printing substrate 02 may be provided. In an advantageous refinement, a cooling unit 33 is provided on the transport path between alignment device 07 and pile delivery 27, in particular downstream of the additional drying unit in the transport path between alignment device 07 and receiving unit 27 (see, e.g., FIG. 1, variant b)). Said cooling unit may be embodied, for example, as a cooling roller 33, which is located between the second conveyor system 26 coming from the alignment device 07 and a third conveyor system 36, e.g. likewise embodied as a revolving gripper conveyor 36, e.g. as a chain gripper system 36. In a further refinement, an inspection unit (not shown), e.g. a surface or line camera, can be provided and can be directed, for example, toward a lateral surface segment of the cooling roller 33 that lies in the transport path.

The alignment device 07 detailed below is generally unrestricted in terms of its embodiments, variants, and configurations, however it preferably is or can be provided in a machine 01 or printing press 01 as described above. In one advantageous embodiment, it is configured in the manner of a module and can be integrated into the transport path of the machine 01 that is to be outfitted by using interfaces, on the input and output sides, to the open section ends of a conveyor system that continues upstream and downstream. A module is understood here, for example, as a structural unit that, at least as a frame unit, can be installed in and removed from the two side sections 48; 49, which are connected via a base and/or cross members.

The device 07 for aligning optically variable image elements 03, e.g. for aligning the optically variable effect in the optically variable coating medium 06 applied previously, e.g. in the form of print elements 08, to the substrate 02, in particular the printing substrate 02, comprises a defined transport path along which the substrate 02 to be conveyed through the alignment device 07 is guided or conveyed in a defined manner from an input region, in which the substrate 02 to be treated, which has the optically variable coating medium 06 on its first side, is or can be fed in past the active components 37; 38; 39; 37*; 38*; 39*; 51; 52 and into an output region. Said first side that has the optically variable coating medium 06 is understood in particular as the side on which the optically variable coating medium 06 is or will be applied or has been applied upstream, for example, in the transport path through the application system 04.

As active components 37; 38; 39; 37*; 38*; 39*, a group of cylinders 37; 38; 39; 37*; 38*; 39* is provided, comprising at least one first cylinder 37; 37* and downstream thereof a second cylinder 38; 38*, which are arranged on different sides of a substrate 02 to be conveyed along the transport path. Said first cylinder 37; 37* is arranged in the transport path of the substrate 02 to be conveyed, on the second side thereof, so that the first side of said substrate, which is coated with optically variable coating medium 06,

11

faces outward during transport of said substrate via the first cylinder 37; 37*. In a preferred embodiment, a third cylinder 39; 39* is provided downstream, arranged on the same side of the transport path as the first cylinder 37; 37*.

In the case of a modular configuration of the alignment device 07, in addition to the aforementioned frame unit such a device may also comprise one, multiple, or all of the cylinders in the group of cylinders 37; 38; 39; 37*; 38*; 39*, already mounted.

In an embodiment or configuration of the alignment device 07 that is referred to here as the basic embodiment or configuration, the first cylinder 37 has, in the region of its outer circumference, a plurality of elements 41 that induce a magnetic field, hereinafter also referred to simply as magnetic elements 41, which serve to orient at least a portion of the magnetic or magnetizable particles of the coating medium 06 applied to the passing printing substrate. In the case of the aforementioned plurality of copies 09 per substrate section or substrate sheet 02, a plurality of rows of magnetic elements 41 are provided over said circumference, spaced apart from one another transversely to the direction of transport, which correspond, when wound off onto the substrate 02, with the pattern of image elements 03 on the substrate 02 that are to be exposed to magnetic fields. The cylinder 37 comprising the magnetic elements 41 is also referred to in the following as a magnetic cylinder 37. With the aforementioned guidance of the substrate 02 in such a way that the first side of said substrate faces outward as it is being transported via the first cylinder 37, the particles are aligned or oriented through the substrate 02 by means of the magnetic elements 41. In this basic embodiment or configuration, the second cylinder 38 is embodied merely as a transport cylinder 38, i.e. without magnetic elements in the region of its outer circumference. In this case the first cylinder 37 is assigned to the alignment device 07, and in particular is not allocated to the application system 04 and does not act as a printing couple cylinder to form a print position.

In the preferred case in which the alignment device 07 comprises a third cylinder 39 downstream of the second cylinder 38, in the basic embodiment or configuration the third cylinder 39* is also embodied merely as a transport cylinder 39*, i.e. without magnetic elements in the region of its outer circumference (see, e.g., FIG. 12 b).

In a particularly advantageous embodiment or configuration of the three-cylinder configuration, the third cylinder 39 of the alignment device 07 is likewise embodied as a magnetic cylinder 39 and has, as described above in reference to the first magnetic cylinder 37, a plurality of elements 42 that induce a magnetic field in the region of its outer circumference, hereinafter also referred to simply as magnetic elements 42, for orienting at least a portion of the magnetic or magnetizable particles of the coating medium 06 applied to the passing printing substrate 02. The magnetic elements 42 can be arranged on the circumference of the second magnetic cylinder 39 in the same pattern as those of the first magnetic cylinder 37. In that case, the position of said magnetic elements with respect to their location as they are rolled out onto a substrate 02 that is being conveyed along the transport path through the alignment device 07 may coincide with the positions of the first magnetic elements 41, or said magnetic elements may all be offset in the same manner in a circumferential and/or axial direction, for example, from the positions of the first magnetic elements 41. The dimensions of an offset in the respective position may be, for example, such that as they are rolled out onto the substrate 02, the surfaces of the first and second magnetic

12

elements 41; 42 still overlap, continuing in a straight line on one side or spaced from one another slightly, i.e. by no more than half of their extension in the relevant direction. In the case of an offset, they can then act offset from one another on the relevant print element 08. In addition to or in place of the offset, the first and second magnetic elements 41; 42 may also be configured and/or oriented differently, so that they induce field lines that differ from one another in terms of direction and/or pattern in the respective plane of the substrate 02 to be treated.

In the case of web-format substrate 02, a cylinder 37; 38*; 39 embodied as a magnetic cylinder 37; 38*; 39 may be embodied without any holding means acting on the substrate 02. Optionally, suction air openings may be provided on the cylinder circumference, which are connected to a vacuum pump and which ensure that the substrate 02 rests securely on the lateral surface. For the preferred case here of sheet-format substrate 02, holding means 43, e.g. grippers 43 of what is known as a gripper bar, are preferably provided on the circumference of the cylinder 37; 38*; 39, said holding means preferably being capable of receiving the leading end of a substrate sheet 02 to be conveyed via the cylinder 37; 38*; 39 and of holding said sheet over an angular range during a rotation of the cylinder 37; 38*; 39. Suction air openings that are connected via lines to a vacuum pump may additionally be provided on the circumference. Although a magnetic cylinder 37; 38*; 39 of this type likewise serves to transport the substrate 02, in the context of its fitting with the aforementioned magnetic elements 41; 42 it is not regarded or referred to here as a transport cylinder. The magnetic elements 41; 42 can be arranged or arrangeable in or on a plurality of ring elements 44, e.g. between four and seven, in particular between four and six, which are spaced axially from one another and can preferably be positioned in the axial direction, with at least one, preferably a plurality of magnetic elements 41; 42, e.g. between two and twelve, advantageously between five and ten, in turn being arranged or arrangeable in or on said ring elements 44, one after another in the circumferential direction and preferably positionable in the circumferential direction (see, e.g., FIG. 10).

Elements 41; 42 that induce a magnetic field, or magnetic elements 41; 42, are understood here as any magnetically active elements that permanently or switchably induce, at least toward the side of the transport path, a magnetic field (of sufficient strength particularly for the alignment of particles contained in the coating medium 06 on the substrate 02 that is guided over said path, as described here). Said magnetic elements 41; 42 may be in the form of permanent magnets with or without engraving, solenoids, or combinations of multiple permanent magnets and/or solenoids. They can be arranged operationally fixed or moved or movable on the operationally ready cylinder 37; 38*; 39.

In the case of web-format substrate 02, a cylinder 37*; 38; 39* embodied (here in particular solely) as a transport cylinder 37*; 38; 39* has, e.g., a cylindrical lateral surface that is or will be wrapped at least partially by the web-format substrate 02 to be guided along the transport path. In the preferred case of sheet-format substrate 02, preferably provided on the circumference of the transport cylinder 37*; 38; 39* are holding means 46, e.g. grippers 46 of what is known as a gripper bar, by means of which a substrate sheet 02 to be conveyed via the cylinder 37*; 38; 39* is or can be received at its leading end, and is or can be held over an angular range during rotation of the transport cylinder 37*; 38; 39*. It is not essential for the cylinder 37*; 38; 39* designated as a transport cylinder 37*; 38; 39* to have a predominantly closed outer cylinder surface; on the con-

trary, in extreme cases it can merely comprise at least one gripper bar, spaced on a cylindrical shell surface and rotating around the cylinder axis. To avoid the formation of chords during transport of the substrate sheets **02**, however, additional axially extending crosspieces and/or axially spaced support disks or support rings **47** may be provided (see, e.g., FIG. 11). In contrast to the magnetic cylinder **37; 38***; **39**, the active angular segment of the cylindrical shell surface lying in the transport path is predominantly, i.e. more than 50%, open toward the inside, whereas the same segment on the magnetic cylinder **37; 38***; **39** is predominantly, i.e. more than 50%, closed. The active angular segment here is understood as the angular segment that comes to lie beneath the substrate **02** or substrate section during the transport thereof on the relevant cylinder **37; 38; 39; 37***; **38***; **39***.

Each of the two or preferably three cylinders **37; 38; 39; 37***; **38***; **39*** is rotatably mounted at its end faces in frame walls **48; 49**, e.g. side sections **48; 49** of a frame that supports the components of the alignment device **07**.

In a particularly advantageous embodiment, in particular the bearing means (if provided) for receiving the journals of the cylinder **39; 39*** to be arranged at the third site and/or, for example, the bearing means for receiving the journals of the cylinder **38; 38*** to be arranged at the second site as viewed in the direction of transport **T** are configured such that the respective cylinder position can be equipped with either a magnetic cylinder **38***; **39** or a transport cylinder **38; 39***. In an advantageous refinement, the bearing means for receiving the journals of the cylinder **37; 37*** to be arranged at the first site are also configured such that the first cylinder position of the group of cylinders **37; 38; 39; 37***; **38***; **39***, as viewed in the direction of transport **T**, can also be equipped with either a magnetic cylinder **37** or a transport cylinder **37*** (see, e.g., FIG. 12).

This can be achieved, for example, in that magnetic cylinders and transport cylinders **37; 38***; **39; 37***; **38; 39*** are provided with journals of the same diameter, and said journals can be arranged in radial bearings of the same inside diameter that are or are to be seated in the side sections **48; 49** for the relevant cylinder positions, and/or in that, for receiving the journals of the magnetic and transport cylinders **37; 38***; **39; 37***; **38; 39***, radial bearings having the same outside diameter are provided in each case, which can be seated in receiving means provided for the relevant cylinder positions on the frame, e.g. openings or bearing shells having the same inside diameter, provided in the side sections **48; 49**. The latter can be provided directly by the inside width of a frame bore provided in the side section **48; 49** or by the inside width of a bearing ring, e.g. an eccentric adjustment ring, additionally provided in such a frame bore. In an advantageous embodiment, the journals and the bearing configuration for the two different types of cylinders **37; 38; 39; 37***; **38***; **39*** in the at least two, preferably three, cylinder positions of the cylinder group comprised by the alignment device **07** are identical.

The three cylinders **37; 38; 39; 37***; **38***; **39*** or the bearings thereof are preferably provided in the frame in such a way that the three cylinder axles lie substantially in a common plane, for example a horizontal plane. In that case, there should be no distance between the axle of the central cylinder **38; 38*** and the connecting plane through the axles of the two outer cylinders **37; 39; 37***; **39***, or at most a maximum distance of no more than 30 mm, preferably no more than 10 mm.

As a further active component **51** on the transport path of the substrate **02**, in particular printing substrate **02**, to be conveyed through the alignment device **07**, at least one first

drying and/or curing unit **51** preferably is or can be arranged on the first side of said substrate, which has the optically variable coating medium **06**. Said unit is directed, as viewed in the direction of transport **T**, toward a lateral surface segment of the first cylinder **37**, e.g. embodied as a magnetic cylinder **37**, or toward a point on the transport path along which the substrate **02** to be conveyed is guided during operation, in particular with its second side, on the first cylinder **37; 37*** embodied, e.g., as a magnetic cylinder **37**.
5 With the aforementioned guidance of the substrate **02** in such a way that its first side faces outward during transport of said substrate via the first cylinder **37; 37***, direct drying or curing of at least an outer layer of coating medium **06** that is applied to the substrate **02** takes place. The point, as viewed in the direction of transport **T**, toward which the first drying and/or curing unit **51** is directed is preferably located at least 90° behind the point at which the substrate **02** to be conveyed along its transport path runs onto the first cylinder **37; 37*** and in front of the point at which the substrate **02** to be conveyed along its transport path via the first cylinder **37; 37*** leaves the first cylinder **37; 37***. Said drying and/or curing unit **51** is preferably embodied as a radiation dryer, which operates on the basis of electromagnetic radiation, e.g. with IR or preferably UV radiation. For this purpose, it comprises one or more radiation sources, e.g. IR or preferably UV light sources.

In a preferred embodiment of the aforementioned first drying and/or curing unit **51**, said unit is configured to act, in at least one operating mode, on the substrate **02** to be treated in sections that are spaced apart from one another rather than continuously over the entire width of said substrate. Said sections are preferably adjustable in terms of their position transversely to the direction of transport of the substrate **02**, and the respective effective width of said sections can optionally be defined.

In a first variant (see, e.g., FIG. 8), the drying and/or curing unit **51** can comprise a plurality of dryer elements and/or curing elements **53**, e.g. dryer heads **53**, e.g. between four and seven, in particular between four and six, arranged 30 side by side transversely to the direction of transport **T** and directed toward the transport path, which are preferably variable in terms of their position transversely to the direction of transport **T**. The dryer heads **53** are preferably embodied as radiation dryer heads **53** and can each comprise one or more radiation sources, e.g. IR or preferably UV radiation sources. In an advantageous embodiment, the dryer heads **53** each comprise a plurality of radiation sources (e.g. more than 10) configured as LED's, e.g. IR LED's or preferably UV LED's, which are arranged at the head end of the respective dryer head **53**, for example in the manner of a one-dimensional or preferably a two-dimensional array. The dryer heads **53** are arranged, for example, on a crossbar and are preferably movable transversely on said crossbar, thus enabling their position to be adjusted.

55 In an advantageous refinement, the drying and/or curing unit **51** that comprises the crossbar and the dryer heads **53** is embodied as a structural unit, e.g. a module, and as such can be installed in or on the side sections **48; 49** of the frame and removed therefrom. The side sections **48; 49** of the frame have, e.g., connection elements or connection points furnished accordingly for this purpose. In an embodiment or configuration in which the first cylinder **37*** is configured as a transport cylinder **37***, the first drying and/or curing unit **51** may be omitted or may be removed during retooling.

In a refinement of the first variant that is especially advantageous particularly in connection with the present production of optically variable image elements **03**, at least

15

one masking element (not shown here) and one fastening mechanism are provided per dryer element and/or curing element 53, said fastening mechanism being intended for positioning the masking element in the radiation path between the dryer element and/or curing element 53 and the transport path so as to effect a defined limitation of the irradiated area in the plane of the transport path in relation to the irradiated area during operation without masking. Masking elements of different sizes can be provided for the purpose of different degrees of shading, and/or the masking element can be movable with at least one component transversely to the beam direction in relation to the dryer and/or curing element 53.

In a second variant that is particularly advantageous with respect to its variability (see, e.g., FIG. 9), the drying and/or curing unit 51 can be a dryer element and/or curing element 54 that extends, in particular in the form of a beam, e.g. in the manner of a light bar 54, in particular an LED light bar, transversely to the direction of transport T over at least the width of the maximum substrate width to be treated in the device 07, and that comprises a plurality, in particular a multiplicity, of radiation sources, e.g. IR or preferably UV radiation sources, e.g. more than 100, arranged immediately side by side transversely to the direction of transport T, i.e. spaced at least by less than 5 mm, in particular at least by less than 2 mm from one another the transverse direction. Said radiation sources can preferably be configured as LED's, e.g. IR LED's or preferably UV LED's, and can be arranged, for example, in a one-dimensional or preferably a two-dimensional array. The light sources can be arranged in or on a one-part or multi-part frame section, for which, in contrast to the dryer element and/or curing element 53 from the first variant, no axial mobility is provided to allow adjustment of the intended beam position. The aforementioned sections in which the substrate 02 is to be acted on are or are to be formed by groups of active radiation sources or radiation sources that are to be activated, between which are groups of inactive light sources or light sources that are not to be activated. The position and preferably the width of the sections can be varied by defining those radiation sources that are active or are to be activated. Groups of radiation sources may be fixedly defined in advance and selectable only as belonging to the active or inactive groups. In an even more variable embodiment, the positions and widths of the sections can be defined by the formation of groups of radiation sources or sub-groups of radiation groups that are to be activated. Although this variant already provides good resolution between the area to be irradiated and the area not to be irradiated, it is also possible for mask elements to be provided, which are positioned in a manner comparable to the first variant in the radiation path between dryer and/or curing element 54 and transport path in such a way that the irradiated area in the plane of the transport path can be even more limited as compared with the irradiated area during operation without masking, for example by blocking residual diffuse beam portions. In this case as well, mask elements of different sizes and/or a relatively movable arrangement may be provided.

In an advantageous refinement of a second variant, the drying and/or curing unit 51 is embodied as a structural unit or module and as such can be installed in its entirety in or on the frame walls or side sections 48; 49 of the frame and removed therefrom, in which case the side sections 48; 49 of the frame have, e.g. connection elements or connection points, furnished accordingly for this purpose. In an embodiment or configuration in which the first cylinder 37* is

16

configured as a transport cylinder 37*, the first drying and/or curing unit 51 may be omitted or may be removed during retooling.

In cases in which another magnetic cylinder 38*; 39 is or 5 may be provided in the transport path through the alignment device 07, preferably in cases in which the third cylinder 39 is embodied as a magnetic cylinder 39, a second drying and/or curing unit 52 is provided as an additional active component 52 on the transport path of the substrate 02, in 10 particular printing substrate 02, to be conveyed through the alignment device 07. Said second drying and/or curing unit is preferably directed, as viewed in the direction of transport T, toward a lateral surface segment of the third cylinder 39, embodied, e.g., as a magnetic cylinder 39, or toward a point 15 on the transport path at which the substrate 02 to be conveyed is guided during operation on said additional magnetic cylinder 38*; 39, although in principle it may also be provided downstream thereof. The point, as viewed in the direction of transport T, toward which the second drying 20 and/or curing unit 52 is directed is preferably once again located at least 90° downstream of the point at which the substrate 02 to be conveyed runs onto this additional magnetic cylinder 38*; 39 along its transport path, and upstream 25 of the point at which the substrate 02 to be conveyed along its transport path via said cylinder 38*; 39 leaves said cylinder 38*; 39 again. It may be advantageous for the circumferential length between the point at which the substrate 02 runs onto the additional magnetic cylinder 38*; 39 and the point at which the second drying and/or curing unit 52 acts to correspond approximately to the corresponding 30 circumferential length on the first magnetic cylinder 37, i.e. up to ±10% of whichever value is greater. The second drying and/or curing unit 52 is preferably embodied as a radiation dryer and preferably operates based on electromagnetic radiation, e.g. with IR or preferably UV radiation. For this purpose, it comprises one or more radiation sources, e.g. IR or preferably UV light sources.

The second drying and/or curing unit 52 can generally be 40 configured in accordance with the first variant of the first drying and/or curing unit 51, for curing or for drying points on print elements 08 that have been applied individually to the substrate 02 but have not yet been dried or cured, for example. Here, the above-described is to be applied accordingly.

In an embodiment that requires relatively little complexity, however, a dryer element and/or curing element 56 extends continuously over the required width, e.g. at least the width of the maximum substrate width to be treated in the device 07, e.g. in the manner of a light bar 56, in 45 particular an LED light bar, which comprises, transversely to the direction of transport, a plurality of radiation sources, e.g. IR or preferably UV radiation sources, in particular a multiplicity thereof, e.g. more than 100, arranged immediately adjacent to one another, i.e. less than 10 mm apart from 50 one another. As with the second variant of the first drying and/or curing unit 52, the radiation sources can preferably be embodied as LED's, e.g. as IR LED's or preferably as UV LED's, and can be arranged, for example, in a one-dimensional or preferably a two-dimensional array. Although this 55 is not mandatory, the dryer element and/or curing element 56 may optionally be embodied as switchable in terms of a sectionwise operation corresponding to the aforementioned second variant of the first dryer element and/or curing element 54.

In an advantageous refinement, the second drying and/or curing unit 52 that comprises the dryer element and/or curing element 56 is embodied as a structural unit or module

and as such can be installed in its entirety in or on the side sections 48; 49 of the frame and removed therefrom, in which case the side sections 48; 49 of the frame have, e.g., connection elements or connection points furnished accordingly for that purpose. In an embodiment or configuration in which the third cylinder 39* is configured as a transport cylinder 39*, the second drying and/or curing unit 52 may be omitted or removed during retooling. If the second cylinder 38*, rather than the third cylinder 39*, is embodied or configured as a magnetic cylinder 38*, the second drying and/or curing unit 52 can be installed at appropriately prepared end points on the second cylinder 38*.

If, as is preferred, the alignment device 07 or the machine 01 that comprises said device is configured for handling and treating sheet-format substrate 02, in particular substrate sheets 02, the alignment device 07 comprises, in addition to the at least two and particularly three aforementioned cylinders 37; 38; 39; 37*; 38*; 39*, a transfer point on the input side, at which a substrate sheet 02 to be treated is or can be transferred from the upstream conveyor system 19 to the first cylinder 37; 37* of the alignment device 07, and comprises on the output side a transfer point at which a treated substrate sheet 02 is or can be transferred from the last cylinder 38; 39; 38*; 39* in the cylinder group comprised by the alignment device 07 to a downstream conveyor system 26. In the case of either upstream or downstream transport cylinders, the respective transfer point can generally be formed by the cooperation of a last or first transport cylinder with the first or last cylinder 37; 38; 39; 37*; 38*; 39* of the alignment device 07. In the present case of conveyor systems 19; 26 embodied as revolving gripper conveyors 19; 26, however, the input-side transfer takes place between a gripper bar 22 of the upstream revolving gripper conveyor 19 and the first cylinder 37; 37* and the output-side transfer takes place between the last cylinder 38; 39; 38*; 39* in the cylinder group and a gripper bar 29 of the revolving gripper conveyor 26 that follows said cylinder downstream. The transfer or receiving by the gripper bars 22; 29 preferably takes place in the region where the turn is effected by the respective chain gripper wheel 24; 31, in particular at the level where the transport path intersects with the plane that connects the axle of the chain gripper wheel 24; 31 with the axle of the cylinder 37; 38; 39; 37*; 38*; 39* in question. In an advantageous embodiment, the axle of the chain gripper wheel 24; 31 and the axle of the cylinder 37; 38; 39; 37*; 38*; 39* in question are situated on a vertical plane.

The three-cylinder configuration of the alignment device 07 in the embodiment for handling sheet-format substrate 02 preferably comprises three cylinders 37; 38; 39; 37*; 38; 39* mounted in end-face side sections 48; 49, along with two chain gripper wheels 24; 31; 24'; 31' on at least one of the side sections 48; 49. In an advantageous refinement, the side sections 48; 49 together with crossbars and/or base plates that connect said side sections, the cylinders 37; 38; 39; 37*; 38; 39*, and in an advantageous refinement the chain gripper wheels 24; 31; 24'; 31' are configured as a module in the manner of a structural unit and as such can be installed as a single component in the machine 01 or removed therefrom.

In general, the cylinders 37; 38; 39; 37*; 38; 39* of the cylinder group can be driven by one or more drive motors assigned solely to these cylinders 37; 38; 39; 37*; 38; 39*, e.g. jointly by one or individually by multiple closed-loop position controlled servomotors.

However, in an advantageous embodiment of the alignment device 07 or machine 01 configured for handling and

treating sheet-format substrate 02, in particular substrate sheets 02, the cylinders 37; 38; 39; 37*; 38*; 39* of the cylinder group are driven by the revolving gripper conveyor 19; 26 disposed upstream or downstream, in particular via at least one of the two continuous pulling means 21; 28; 21'; 28', in particular continuous chains 21; 28; 21'; 28' of the revolving gripper conveyor 19; 26 in question, in particular the chain gripper system 19; 26. For example, driving is effected via a revolving conveyor 19; 26 on an outer one of the cylinders 37; 38; 39; 37*; 38*; 39*, e.g. the first cylinder 37; 37*, and from there to the remaining cylinders 38; 39; 38*; 39* in succession. For this purpose, for example, at least one and preferably both chain gripper wheels 24; 24', which are situated opposite one another on the sides of the machine, are arranged for conjoint rotation on a shaft 58, on which a gearwheel 57 is also arranged for conjoint rotation. Said gearwheel 57 meshes directly or via an even number of intermediate gearwheels with a gearwheel 59, which is connected for conjoint rotation to the axle of the cylinder 37; 38; 39; 37*; 38*; 39* to be driven, e.g. the first cylinder 37; 37*. Said gearwheel 59 or another gearwheel, which is likewise arranged for conjoint rotation on the axle, meshes with a gearwheel 61, which is connected for conjoint rotation to the axle of the adjacent cylinder 37; 38; 39; 37*; 38*; 39*, e.g. the second cylinder 38; 38* of the cylinder group. Finally, in the case of three cylinders 37; 38; 39; 37*; 38*; 39* the latter gearwheel 61, or an additional gearwheel arranged for conjoint rotation on the same axle meshes with a gearwheel 62, which is connected for conjoint rotation to the axle of the remaining cylinder 37; 38; 39; 37*; 38*; 39*, e.g. the third cylinder 39; 39*. If processing will continue from the alignment device 07 to the other, e.g. downstream conveyor system 26, the latter gearwheel 62 or another gearwheel arranged for conjoint rotation on the same axle meshes directly or via an even number of intermediate gearwheels with a gearwheel 63, which is connected for conjoint rotation to a shaft 64, which bears at least one of the chain gripper wheels 31; 31' for conjoint rotation.

In the described embodiment for handling sheet-format substrate 02, in particular printing substrate 02, the substrate 02 is preferably transferred directly between cylinders 37; 38; 39; 37*; 38*; 39* of the cylinder group that are adjacent to one another in pairs. To prevent flapping and/or grinding, a guide device having blower openings that face the transport path may be provided in the transport path at one or more of the cylinders 37; 38; 39; 37*; 38*; 39*. To avoid friction-induced damage to the coated first side of the substrate 02 during its transfer from the conveyor system 19 to the first cylinder 37; 37*, a guidance unit 73, e.g. an air module having blower air openings that face the transport path, may be provided in the region where the direction of the movement path of the gripper bars 22 changes, said blower air openings supporting the substrate sheet 02 during the change in direction.

In a variation of the aforementioned two-cylinder basic embodiment or configuration, the second cylinder 38* may be embodied as a magnetic cylinder 38* having an above-described pattern of circumferentially arranged magnetic elements 41, 42 or may be configured in this way by retrofitting the basic configuration. In a further variation of the configuration of the two-cylinder group, for example for operation without alignment of a variable image element, both cylinders 37*; 38 may be configured or configurable as transport cylinders 37*; 38.

In the described and preferred case involving a cylinder group with three cylinders 37; 38; 39; 37*; 38*; 39*, in contrast or as an alternative to the aforementioned particu-

larily advantageous embodiment or configuration (see, e.g., FIG. 12 c)), various other embodiments or configurations may be implemented and may be advantageous:

If only a single-stage orientation of particles contained in the coating medium 06 is provided or required, then in the alignment device 07, as in the basic embodiment, a magnetic cylinder 37 may be provided at only one of the cylinder positions for the cylinders 37; 38; 39; 37*; 38*; 39*, e.g. that of the first cylinder 37, and cylinders 38; 39* configured only as transport cylinders 38; 39* may be provided at the other cylinder positions (see e.g. FIG. 12 b)).

However, if, for example, a machine 01 containing the alignment device 07 in the transport path is to be operated using a different production process in which, rather than the printing ink 06 that contains the alignable particles, a different printing ink is used, an advantageous configuration may be one, for example, in which a cylinder 37*, 38; 39* configured merely as a transport cylinder 37*; 38; 39* is or will be provided at each of the three cylinder positions (see e.g. FIG. 12 a)).

In the above-described particularly advantageous embodiment or configuration in which the first and third cylinders 37; 39 are magnetic cylinders 37; 39 and the second cylinder 38 is a transport cylinder 38 (see, e.g., FIG. 12 c)), a two-stage alignment can be carried out, the alignment taking place from the same side of the transport path in each case.

In an embodiment or configuration that is different therefrom, in which magnetic cylinders 37; 38* are provided at two adjacent cylinder positions, e.g. at those of the first and second cylinders 37; 38*, and a transport cylinder 39* is provided at the other, e.g. third cylinder position, a two-stage alignment is enabled, but from different sides of the transport path (see, e.g., FIG. 12 d)). In this embodiment or for this configuration option, however, it is advantageous if the aforementioned second drying and/or curing unit 52 or a comparable drying and/or curing unit is or can be provided on the transport path around the second cylinder 38*. Corresponding connection elements or connection points may be provided, for example.

Finally, in a further embodiment or configuration, all three cylinder positions may be equipped with cylinders 37; 38*; 39 configured as magnetic cylinders 37; 38*; 39 (see e.g. FIG. 12 e)). This makes it possible, for example, following the first alignment of particles of a coated print element 08 and a partial drying or curing in only a portion of the print element 08, to at least partially disperse the order of the particles present in the uncured or undried section on the second magnetic cylinder 38* and/or even to prepare an orientation to be performed on the third magnetic cylinder 39.

If, in an aforementioned embodiment or configuration, the second cylinder 38* is embodied as a magnetic cylinder 38*, it is advantageous for the magnetic elements comprised by said cylinder on the circumference thereof to be arranged with their surfaces that face the transport path offset radially inward from the surfaces that support the substrate 02 on a cylindrical shell surface, i.e. not flush with the supporting surface. This prevents any as yet undried coating medium 06 from being smeared as a result of contact with the magnetic elements.

On the circumference of the cylinder 37; 38*; 39 configured as a magnetic cylinder 37; 38*; 39, a smoothing device, e.g. a plurality of axially spaced reels or one or more rollers, may be provided, which is or can be engaged over the substrate 02 on the cylinder 37; 38*; 39 in the transport path of the substrate 02 between the run-up point thereof and the point of drying or curing.

In an advantageous refinement of the cylinder 37; 38*; 39 configured as a magnetic cylinder 37; 38*; 39, said cylinder can comprise a transmitter, e.g. a coupler, for transmitting electric energy and/or control signals from outside into the rotating cylinder 37; 38*; 39.

In an advantageous embodiment of the alignment device 07, each cylinder 37; 38*; 39 configured as a magnetic cylinder 37; 38*; 39 is equipped with its own vacuum pump for supplying suction air to suction air openings provided on its lateral surface.

The cylinder 37; 38*; 39 configured as a magnetic cylinder 37; 38*; 39 may be configured, e.g. as depicted in FIG. 10, without a covering between the ring elements 44 that bear the magnetic elements 41; 42, and can optionally have additional supporting rings between the ring elements 44, or a covering, e.g. a cover plate, in which regions are hollowed out for the magnetic elements 41; 42 and which has bores, for example, as suction air openings.

In an embodiment of the magnetic cylinder 41; 42 that is advantageous in terms of format variability and/or variability in the position of the variable image elements 03 on the substrate 03 or the copies 09 (see, e.g., FIG. 13), at least two adjacent ring elements 44 but preferably all of said axially movable ring elements that contain or can be equipped with the magnetic elements 41; 42 are shaped, at least in a cover element 71 that makes up part of the cylindrical shell surface of the cylinder 39; 38*; 39, on the sides of said element that face one another in the axial direction of the cylinder 37; 38*; 39, in a tooth-like or fan-like manner with protrusions 66, e.g. in the manner of tabs 66 or lugs 66, and with corresponding recesses 67, e.g. cutouts 67 or troughs 67, and are offset in the circumferential direction such that when two adjacent ring elements 44 move axially toward one another, the tooth-like widened sections 66 of one ring element 44 can dip into the corresponding recesses 67 of the other ring element 44. This enables the printing substrate 02 to be supported as uniformly as possible with possible variations in spacing.

Said ring elements 44 may be embodied as single-part or multi-part elements. Said ring elements may be shaped in this tooth-like manner in their entirety, i.e. in the region of their side walls 68; 69 and in the region of the outwardly facing cover elements 71, or in an advantageous embodiment, said ring elements may comprise circular disk-shaped side walls 68; 69 and a cover element 71 that has the recesses 67 and protrusions 66, e.g. covering plates or covering strips 71 that are shaped along their edges in the above-described tooth-like manner.

The cover element 71 may be the outwardly facing wall of a single-piece ring element 44 or a component, e.g. cover plate or cover strip, arranged separately on the ring element 44.

In an advantageous embodiment, the edges of the recesses 67 and protrusions 66 extend in a wavelike manner and are thus formed without sharp corners.

In both cases the cover element 71 has recesses for the magnetic elements 41; 42. A plurality of suction air openings 72 are preferably provided in the respective cover element 71, and negative pressure can be generated in a space lying beneath said cover element between the side walls 68; 69 and the cover element 71 by a line connection to a vacuum pump.

While preferred embodiments of devices, machines, and methods for applying and aligning magnetic or magnetizable particles on a web-format or on a sheet-format, in accordance with the present invention, have been set forth fully and completely hereinabove, it will be apparent to one of

21

skill in the art, that various changes can be made thereof, without departing from the true spirit and scope of the present invention, which is accordingly to be limited only by the appended claims.

The invention claimed is:

1. A device for aligning ones of magnetic and magnetizable particles contained in a coating medium that is applied to a first side of one of a web-format and a sheet-format substrate, the device comprising;

an application system arranged in a transport path of the substrate, by the use of which application system the coating medium one of is and can be applied, at at least one application point, to the first side of the substrate, a first cylinder embodied as a first magnetic cylinder, which first magnetic cylinder is arranged downstream of the application system in the transport path of the substrate to be conveyed and which first magnetic cylinder has, in a region of its outer circumference, a plurality of first elements that induce a first magnetic field,

a second cylinder, which second cylinder is located downstream of the first magnetic cylinder in the transport path of the substrate to be conveyed,

a third cylinder, which third cylinder is located downstream of the second cylinder, and wherein the third cylinder, which is embodied as a second magnetic cylinder, is arranged in the transport path of the substrate to be conveyed, on the same side of the transport path as the first cylinder and has, in a region of its outer circumference, a plurality of second elements that induce a second magnetic field; and

one of a drying and a curing unit, which is arranged on the transport path between a point at which the substrate runs onto the first magnetic cylinder and a point at which the substrate runs onto the third cylinder embodied as the second magnetic cylinder, wherein

the first magnetic cylinder, is arranged in the transport path of the substrate to be conveyed, on a second side thereof, and wherein the one of the drying and the curing unit is arranged in the transport path of the substrate to be conveyed on the first side thereof.

2. The device according to claim 1, wherein the second cylinder is embodied as a transport cylinder, via which transport cylinder the substrate one of is and can be fed from the first cylinder, which is embodied as the first magnetic cylinder, to the third cylinder, which is embodied as the second magnetic cylinder.

3. The device according to claim 1, wherein the second cylinder is embodied as a third magnetic cylinder and which second cylinder has, in a region of its outer circumference, a plurality of third elements that induce a third magnetic field.

4. The device according to claim 3, wherein the second cylinder, which is embodied as the third magnetic cylinder, is arranged on the opposite side of the transport path from the first cylinder, which is embodied as the first magnetic cylinder.

5. The device according to claim 3, wherein the first cylinder, which is embodied as the first magnetic cylinder, and which is provided in the transport path at a first cylinder

22

position, wherein the second cylinder, which is embodied as the third magnetic cylinder, and which is provided at a second cylinder position, and wherein a fourth cylinder that follows the second cylinder, which is embodied as the third magnetic cylinder, and that is provided at a third cylinder position, one of are and can be mounted rotatably in frame walls of a frame.

6. The device according to claim 5, one of wherein bearing means for receiving journals of the second cylinder, which is embodied as the third magnetic cylinder, and which is to be arranged at the second cylinder position are configured such that the second cylinder position can be one of equipped and configured one of with the additional cylinder configured as the second magnetic cylinder having the plurality of second elements that induce a second magnetic field, and corresponding to the first cylinder embodied as the first magnetic cylinder, and with the second cylinder configured as a transport cylinder, and wherein the bearing means for receiving the journals of the fourth cylinder to be arranged at the third cylinder position are configured such that the third cylinder position can be one of be equipped and configured one of with the additional cylinder configured as the second magnetic cylinder having the plurality of second elements that induce the second magnetic field, and corresponding to the first cylinder embodied as the first magnetic cylinder, and with the second cylinder configured as a transport cylinder.

7. The device according to claim 6, wherein the bearing means for receiving the journals of the cylinder to be arranged at the first cylinder position are configured whereby the first cylinder position can be one of equipped and configured with a transport cylinder that corresponds to the second cylinder, rather than with the first magnetic cylinder.

8. The device according to claim 1, wherein the one of the first drying and curing unit comprises a plurality of radiation sources, which plurality of radiation sources are one of provided in a plurality of dryer heads that define a plurality of sections and are provided in an array of radiation sources that is continuous over a maximum width of a substrate to be treated and that can be activated in sections, and wherein the one of the first drying and curing unit comprises a plurality of radiation sources configured as UV LED's and is one of configured to act on the substrate to be treated in sections that are spaced apart from one another transversely to the direction of transport and is directed, in the transport path of the substrate to be conveyed, toward a lateral surface segment of the first cylinder that lies in the transport path and is arranged directed toward a point on the transport path that lies on the circumference of the first cylinder.

9. The device according to claim 8, one of wherein the plurality of sections are adjustable in terms of their position transversely to the direction of transport and wherein the one of the drying and the curing unit one of comprises the plurality of radiation sources, which are provided in a plurality of dryer heads that define the plurality of sections and are provided in the array of radiation sources that is continuous over the maximum width of the substrate to be treated and that can be activated in sections.
